TOWEL BAR

LaVerne E. Clayton, Rockford, Ill., and Martin R. Lambertz, New Hamburg, Ontario, Canada, assignors to Amerock Corporation, Rockford, Ill.

Filed June 24, 1970, Ser. No. 33,637

Term of patent 14 years

Int. Cl. D8—03

U.S. Cl. D33—32

FIG. 1 is a top view of a towel bar incorporating our new design.

FIG. 2 is an enlarged fragmentary front view of the towel bar.

FIG. 3 is an end view of the towel bar as seen from the left in FIG. 2.

FIG. 4 is an enlarged fragmentary sectional view taken along the line 4—4 in FIG. 1.

FIG. 5 is a fragmentary sectional view taken along the line 5—5 in FIG. 2.

FIG. 6 is a sectional view taken along the line 6—6 in FIG. 2.

FIG. 7 is a sectional view taken along the line 7—7 in FIG. 2.

The portions shown in broken lines are for purposes of illustration only.

We claim:

The ornamental design for a towel bar, as shown and described.
